Primary Examiner — Lilyana Bekic

(57) **CLAIM**

The ornamental design for a positive airway pressure assembly, as shown and described.

DESCRIPTION

FIG. 1 is a top view of a positive airway pressure assembly showing our new design;

FIG. 2 is a bottom view thereof;

FIG. 3 is a back view thereof;

FIG. 4 is a front view thereof;

FIG. 5 is a right side view thereof;

FIG. 6 is a left side view thereof;

FIG. 7 is a top, back, left side perspective view thereof;

FIG. 8 is a top, front, right side perspective view thereof; and,

FIG. 9 is a top, front, right side perspective view thereof in an unassembled state.

The broken lines illustrate portions of the positive airway pressure assembly and form no part of the claimed design.

1 Claim, 9 Drawing Sheets
